US00D991174S

(12) **United States Design Patent** (10) Patent No.: **US D991,174 S**
(45) Date of Patent: **** Jul. 4, 2023**

(54) **PHOTOVOLTAIC INVERTER**

(71) Applicant: **Sungrow Power Supply Co., Ltd.**, Hefei (CN)

(72) Inventors: **Xin Ding**, Hefei (CN); **Rui Wang**, Hefei (CN); **Yongjin Liu**, Hefei (CN)

(73) Assignee: **Sungrow Power Supply Co., Ltd.**, Hefei (CN)

(**) Term: **15 Years**

(21) Appl. No.: **29/816,071**

(22) Filed: **Nov. 18, 2021**

(30) **Foreign Application Priority Data**

May 21, 2021 (CN) 202130308008.5

(51) LOC (14) Cl. **13-02**

(52) U.S. Cl.

USPC **D13/110**

(57) **CLAIM**

The ornamental design for a photovoltaic inverter, as shown and described.

DESCRIPTION

FIG. 1 is a front view of a photovoltaic inverter according to the present application, showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front, right, top perspective view thereof;

FIG. 8 is a rear, left, top perspective view thereof;

FIG. 9 is an enlarged view of FIG. 5;

FIG. 10 is an enlarged view of FIG. 6;

FIG. 11 is an enlarged partial view of the area identified as 11 in FIG. 1; and,

FIG. 12 is an enlarged partial view of the area identified as 12 in FIG. 8.

The broken lines shown represent environmental subject matter and form no part of the claimed design.
